Primary Examiner — Antoine D Davis(74) *Attorney, Agent, or Firm* — Drinker Biddle & Reath LLP(57) **CLAIM**

The ornamental design for a spectrometer, as shown and described.

DESCRIPTION

FIG. 1 is a front view of a spectrometer of the first embodiment of our new design.

FIG. 2 is a rear view of the spectrometer of FIG. 1.

FIG. 3 is a top plan view of the spectrometer of FIG. 1.

FIG. 4 is a bottom view of the spectrometer of FIG. 1.

FIG. 5 is a right side view of the spectrometer of FIG. 1.

FIG. 6 is a left side view of the spectrometer of FIG. 1.

FIG. 7 is a top perspective of the spectrometer of FIG. 1.

FIG. 8 is a bottom perspective of the spectrometer of FIG. 1; and,

FIG. 9 is a reference view of the spectrometer of FIG. 1 in use, wherein the spectrometer is connected to a printed circuit board in a printer.

The features shown in dotted lines depict environmental subject matter only and form no part of the claimed design.

1 Claim, 9 Drawing Sheets(56)
